DESIGN FOR A HOUSING FOR BATHTUB FITTINGS

James C. Hermann, Los Angeles, Calif.

Application February 28, 1939, Serial No. 83,472

Term of patent 7 years

To all whom it may concern:

Be it known that I, James C. Hermann, a citizen of the United States, residing at Los Angeles, in the county of Los Angeles and State of California, have invented a new, original, and ornamental Design for Housings for Bathtub Fittings, of which the following is a specification, reference being had to the accompanying drawing, forming a part thereof.

In the said drawing,
Fig. 1 is a front elevational view of a housing showing my new design, and

Fig. 2 is a side elevational view thereof.

I claim:

The ornamental design for a housing for bathtub fittings, as shown.

JAMES C. HERMANN.
